LUBRICATING DEVICE FOR CORK-ROD
PACKING MACHINES

John M. Binder, New Hyde Park, N. Y., assignor to
Consolidated Cork Corporation, New York,
N. Y., a corporation of New York

Application April 17, 1942, Serial No. 439,354

3 Claims.

(Cl. 18—5)

This invention relates to means for filling and packing particles of cork or similar granulated materials into elongated tubes to thereby form the cork into rod-like sections which are subsequently cut into disks used for lining the insides of bottle caps or like articles. An example of such a machine is found in my Patent No. 2,183,928 dated December 19, 1938.

In a machine of this character, a plurality of metal tubes are carried on rotating conveying means and the granulated cork is deposited and packed down into the tubes at a number of filling stations during successive halts in the rotation of the conveying means or turret. The filled tubes are carried away from the turret and subsequently the cork that has been deposited into the tubes and has formed into rod-like sections, is forced out of the tubes and later severed into disk-like sections. To facilitate the ejection or removal of the rods from the tubes in which they are formed, it is desirable to lubricate the inner surfaces of the tubes prior to the filling operation. This is usually done by hand prior to the placement of the tubes on the conveyor that transports them to the filling means.

The primary object of the present invention is to provide tube-lubricating means which will dispense with laborious hand lubrication and which will enable the tubes to be internally lubricated automatically just prior to being carried to the first cork-filling station on the machine.

The invention further contemplates the provision of means by which the tubes are lubricated while disposed in their normal filling position whereby they may successively receive charges of the granulated cork or other filling material directly after having been internally lubricated.

In the accompanying drawings forming a part hereof, Fig. 1 is a vertical sectional view of a structure made in accordance with the invention, the view being taken on the line 1—1 of Fig. 4, looking in the direction of the arrows; Fig. 2 is a vertical sectional view showing the lubricating tube at the lowermost point of its descent into the tube to which the lubricant is applied; Fig. 3 is a sectional view of the lower portion of the lubricating tube showing the attachment of the swab; Fig. 4 is a plan view of the structure of Fig. 1; Fig. 5 is a sectional view on the line 5—5 of Fig. 4, looking in the direction of the arrows; Fig. 6 is a vertical sectional view through the valve of Fig. 5; and Fig. 7 is a sectional view

on the line 7—7 of Fig. 6, looking in the direction of the arrows.

In the accompanying drawings portions of a tube-filling machine are disclosed, the machine being similar to that disclosed in my Patent No. 2,183,928 and provided with a novel means for internally lubricating the tubes in which the ground cork is packed.

The machine in which the lubricating mechanism is employed, includes a vertically disposed stationary cylinder 1 provided with two slots 2 and 3 through which the cross-head 4, attached by means of the bearing 5 to a push rod 6, moves a plunger head 7 up and down. The head 7 carries a plurality of downwardly extending plungers 8 which, upon the descent of the plunger head 7, enter the tubes 10 carried below them, and pack the cork down in the tubes. The hopper from which the ground cork is fed into the tubes is indicated at 9, and below the same is arranged a plurality of filling stations 11 at which the tubes 10 halt and into which cork granules descend from the hopper and, by means of a feeder member 12, are caused to descend 20 into a funnel or chute 13 located above the tube 10 to be filled.

The tubes to be filled are carried on an intermittently rotated turret 14 rotatably mounted on the roller bearings 15 on top of a flange 16 on the table top 17. During pauses in the rotative movement of the turret 14 the tubes are each internally lubricated and thereafter receive successive charges of cork which is packed or tamped down by means of the rods 8. All of 30 these elements form part of the machine disclosed in my Patent No. 2,183,928.

The tubes to be lubricated and thereafter filled, are disclosed at 10b in Fig. 4, wherein it will be seen that the same are held in vertical position 40 and moved along toward the turret 14 by means of a chain conveyor 18. When each tube reaches the turret, it is delivered onto the same to reach a position under the lubricating means. Said means includes a downwardly dependent tube 19 provided at its lower end with a cylindrical brush or swab 20, having a shank 20a fitting into the end of the tube 19 and secured therein by the screw 20b. The brush or swab 20 is so arranged that upon descent of the plunger head 7, 45 the brush or swab 20 will descend down into the tube 10c and apply lubricant over the entire inner face of the tube.

The lubricating tube 19 is secured in the radially extending flanges 21 and 22 of the plunger head 7 by means of the screws 23 and near its

lower end and just above the brush or swab 20, the lubricating tube 19 is formed with a plurality of holes 24 through which the lubricant can pass from inside the tube and reach and saturate the brush or swab 20.

The top of the cylinder 3 is provided with a cap member 25 provided with a centrally located post 26 that supports a disc or plate 27 from which hangers or straps 28 extend. Projecting radially from the head 25 and below the disc 27 is an arm 29 that supports a valve 30; the details and operation of which are closely disclosed in Figs. 5 and 6. The valve is provided with a top portion 31 closing the upper end of the housing 31a and formed with a passage 32 and a downwardly dependent tubular part 33 through which a supply of lubricant is delivered to the interior of the housing 31a of the valve. Passage 32 is connected through pipe 34 and valve 35 to a tank 36 in which a supply of the lubricant is contained. The tank 36 may be supported in any suitable manner adjacent to the machine, and as shown is held by the straps 37. A gauge glass 38 is provided on the tank for determination of the quantity of lubricant contained within the same.

Vertically movable within the valve housing 31a is the valve member 39 which is provided with a conical head 40 normally adapted to be held against the seat 41 to thereby close the outlet 42 leading from the valve housing 31a. A spring 43 is located within the valve member 39 and normally tends to maintain the head 40 in contact with the seat 41 as clearly indicated in Fig. 6 to thereby close the outlet 42. The valve member 39 is formed with a plurality of radial slots 44 so that lubricant flowing from the tubular part 33 may pass through the slots 44 to reach the interior of the housing 39 and when the valve is open or in the position shown in Fig. 3, it will pass out of the outlet opening 42.

Directly below the valve 30 is a funnel 45 carried by the flange 21 of plunger head 7, said funnel having a base or bottom plate 46 adapted to contact with the stem portion 47 extending downwardly from the valve 39 and elevate the valve member as indicated in Fig. 5 to permit the flow of lubricant into the funnel 45 and from thence through the spout 48 communicating with the top or open end of the lubricating tube 19. It will thus be apparent that each time that the plunger head 7 is raised, the base plate 46 of funnel 45 will strike against the lower end of the stem 47 and raise the valve member 39 from off the seat 41 to permit a flow of lubricant down into the lubricating tube 19. The lubricant so applied to the interior of the tube 19 will flow out through the holes 24 and saturate the brush or swab 20.

Upon the descent of the plunger head 7, the tube 19 and the brush or swab 20 carried thereby, will be forced down into the interior of the tube 10c to apply a lubricating coating to the inside wall surface of the same. Upon rising movement of the plunger head 7, the tube 19 will be elevated to the raised position shown in Fig. 1 where it will receive another charge of lubricant and the tube 10c that has been lubricated will then be moved to the first filling station 11 where it will receive its first charge of ground cork and will thereafter continue from one filling station to the next until it reaches the last filling station indicated at 50 in Fig. 4, from whence it will be delivered to the chain conveyor 18 and be carried away from the turret 14. The filled tubes be-

ing carried away from the turret are indicated at 10d in Fig. 4.

From the foregoing, the operation of the device will be readily understood. The tubes to be filled with cork are carried by the conveyor as indicated at 10b and successively reach a position beneath the lubricating rod 19 which, upon descent of the plunger head 7, swabs the interior of each tube. Upon rising of the plunger head 7, the tube thus lubricated will be moved to the first filling station.

The application of lubricant to the interior of each tube just prior to the disposition of the first charge of cork therein ensures the cork being deposited into a freshly lubricated tube and permits the easy ejection or removal of the finished cork rod after the tubes with the cork rods formed therein have been removed from the machine. The employment of a lubricating device of this character in combination with a cork filling machine ensures lubrication of the tubes directly prior to filling so that drying out of the lubricant within the tube before the filling takes place never occurs.

While I have described one embodiment of my invention, it is obvious that the same is not to be restricted thereto, but is broad enough to cover all structures coming within the scope of the annexed claims.

What I claim is:

1. In a machine of the character described, means for filling pulverized cork or the like into tubes, a rotative turret on which the tubes are transported, a post around which the tubes are carried by the turret, a reciprocating carrier movable on the post and carrying plungers for packing the cork in the tubes, a swab carried by said carrier and adapted to be thrust downwardly into each tube before the tube is carried by the turret to the filling means, a lubricant-supply means mounted above the carrier, said lubricant-supply means including a tank, a valve connected thereto and located above the swab, said valve including a downwardly projecting stem, and an abutment carried by the carrier and adapted to be brought into contact with the valve stem upon raising movement of the carrier, to thereby open the valve, and means for delivering lubricant from the outlet of the valve to the swab when the valve is so opened.

2. A lubricating device for tubes adapted to receive a filling of cork particles, comprising, means for supporting a tube in a vertical position, a reciprocating carrier mounted above the tube, a hollow shaft dependent vertically from the carrier, a swab on the end of said hollow shaft and carried thereby into the interior of the tube to lubricate the inside surface of the tube, a lubricant-container having a valve located in fixed position above the hollow shaft to one side of the vertical axis of the same, means for normally holding the valve closed, an operating stem dependent from the valve, a funnel mounted on the carrier in position to surround the operating stem when the carrier is raised to elevated position, a spout extending from the funnel and communicating with the interior of the hollow shaft, and an abutment within the funnel for contact with the operating stem of the valve to open the valve and cause a charge of lubricant to be delivered into the funnel each time that the carrier reaches its elevated position.

3. A lubricating device for tubes adapted to receive a filling of cork particles, comprising, means for supporting a tube in a vertical posi-

tion, a reciprocating carrier mounted above the tube, a hollow shaft dependent vertically from the carrier, a swab on the end of the shaft and carried thereby into the interior of the tube to lubricate the inside surface of the tube, a lubricant-container provided with a valve having an operating stem extending downwardly towards the carrier and to one side of the tube, a funnel

on the carrier provided with a bottom for impingement against the valve-operating stem to open the valve when the carrier is raised, the side wall of the funnel having a laterally directed spout in communication with the interior of the hollow shaft to direct lubricant from the funnel into said shaft.

JOHN M. BINDER.
